UNITED STATES PATENT OFFICE.

HENRY J. KEMPF, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

WRAPPING-MACHINE.

1,194,505.

Specification of Letters Patent. Patented Aug. 15, 1916.

Application filed January 17, 1914. Serial No. 812,657.

To all whom it may concern:

Be it known that I, HENRY J. KEMPF, a citizen of the United States of America, residing at Springfield, in the county of 5 Hampden and State of Massachusetts, have invented new and useful Improvements in Wrapping-Machines, of which the following is a specification.

This invention relates to wrapping machines. It is a very common practice in 10 wrapping many articles, such for instance as bars of chocolate, to insert a card in the package formed by the wrapping operation. Sometimes this card serves merely for advertising purposes, but more frequently it is 15 used for the purpose of stiffening the package and protecting the wrapped article from breakage. The handling of a plurality of pieces of wrapping material in this manner 20 requires a relatively complicated mechanism; and this is particularly true in machines designed to wrap food stuffs, or confections, which require more than one wrapper. For instance, cakes of chocolate 25 are usually wrapped in a tin foil or other moisture-proof wrapper, and also in an outer wrapper or band, the card being inserted between the inner wrapper and the band.

30 The present invention aims to simplify the mechanisms designed to handle wrapping materials of this character; and it is directed specifically to the solution of the problems presented in introducing a card 35 into a package. The manner in which it is proposed to solve these problems will be readily understood from the following description of a machine similar to that shown in Patent No. 895,945, granted August 11, 40 1908, the machine of this patent, however, being modified in accordance with the present invention.

In the specific machine hereinafter described it is proposed to make use of some 45 suitable adhesive material to effect the transfer of a card with a wrapper or band with which it is to be associated, and thus to avoid the necessity of a separate card transferring mechanism.

50 In the drawings: Figure 1 is a top plan view of a part of my machine; Fig. 2 is a sectional view taken on the lines 2-2 of Fig. 1 of the mechanism for handling the paper wrapper and the band; Fig. 3 is a

sectional view of the machine taken on the 55 lines 3-3 of Fig. 1; Fig. 4 is a side elevation of a portion of the machine; and Fig. 5 is a section of a modification thereof.

In its general arrangement, my machine is broadly similar to that disclosed in the 60 patent to Berger above referred to and the wrapping mechanisms, shears, etc., are operated in the same fashion. For that reason, they have not been shown in the drawings, which rather are concerned with the real 65 subject-matter of the invention which is the manipulation and insertion of a card between the paper wrapper and the band prior to the actual wrapping operation.

In the drawings, the supporting frame-work of the machine is represented by A. The main-shaft 1, supported in the frame-work A, carries a large driven-gear 2 and drives by bevel-gears the counter-shaft 3 supported in brackets 4 upon the frame-work A. The paper feed is not shown in detail, it being understood that this mechanism is substantially like that shown in the Berger patent above referred to. It will be sufficient here to say that the paper p is 70 fed through a depression 5 in the top-plate 6 of the machine and cut off at the appropriate moment by shears 7. Located at the rear of the depression 5 in the plate 6 in my machine are a pair of brackets 8 upstanding 75 from the frame-work A which carry a small shaft 9 upon which is a daub-wheel 10 having a projecting lug 11 thereupon.

Associated with one of the brackets 8 is a bracket 12 which carries the short shaft 13 80 driven by the sprocket 14 and carrying at its opposite end the lugs 15. A glue-box 16 is seated in a recess in a plate 16' secured to the frame-work A above the path of the paper, this glue-box carrying bearings for 85 the shaft 17 which carries the wheel 18; and the box is removably secured in place by the hand-screw 19, the arrangement being such that the entire glue-box may be removed for cleaning merely by the loosening of the 90 hand-screw 19. The shaft 17 carries upon its ends a pair of lugs 20 for coöperation with the lugs 15 whereby, when inserted in place, the shaft of the glue-box is positively 95 rotated from the shaft 13. Upon the shaft 100 13 is a gear 21 which meshes with a gear 22 upon shaft 9 as clearly seen in Fig. 1, the result obviously being that the shaft 9 is 105

positively rotated to apply a small patch of adhesive to the paper passing thereunder each time lug 11 on wheel 10 comes in contact with the paper, the lug 11 in turn taking

5 up adhesive from the wheel 18. This adhesive mechanism is driven by the chain 25 from a sprocket upon the counter-shaft 3 as clearly shown in Fig. 2.

Located above the depression 5 in the top- 10 plate 6 of the machine is the band-magazine 30, having at one side thereof the suction withdrawing device 31, substantially like that disclosed in the Berger patent above referred to, and operable from the side of the

15 band-magazine toward the shears 7 is a nipper 32, as suggested in Fig. 1, adapted to seize the leading end of the band and the leading end of the wrapping paper together and to draw these two wrappers to the wrap-

20 ping elements of the machine, all in the fashion shown in Berger, save that I here employ and find it necessary to use only one nipper where Berger uses an independent nipper for the band and for the wrapping

25 paper, respectively. A path-cam 40 upon the main-shaft 1 drives the reciprocating slide 41 in a manner clearly shown in Fig. 3. The forward end of this slide is forked as shown in Figs. 1 and 3 and comprises a

30 pair of prongs 42 (only one of which is shown in Fig. 3) and a small plate 44 forming a shoulder to carry forward the bottom card of a pile of cards 45 carried in a suitably arranged receptacle 46 and pressed

35 downwardly by the weight 47, all as shown in Fig. 3. Upon each reciprocation of the slide 41, a card is introduced thereby above the wrapping paper *p* and beneath the bottom plate of the band-magazine 30 and lo-

40 cated substantially centrally of the wrapping paper *p* in the recess 5 of the top-plate 6. Upon the counter shaft 3 is a cam 50 co-operating with a roller 51 upon a recipro-

45 cally shaft 52 sliding in bearings 53 upon the frame-work A and carrying at its upper end the block 54 which reciprocates in the recess 55 in the top-plate 6 substantially midway thereof. This mechanism serves to force the card and the paper together at the

50 point where adhesive is supplied between the two whereby the card and paper will thereafter adhere to each other as the paper is drawn through the machine, and the forks 42 on slide 41 may be withdrawn without

55 disturbing the card.

The operation of my machine is briefly as follows: The wrapping paper is fed through the recess 5 from an indefinite supply. The display or covering bands are supplied to their magazine 30. With the parts in the position illustrated in Fig. 1, the slide 41 introduces a card above the wrapping paper *p* and below the bottom-plate of the band-magazine. Previous to this operation, the adhesive devices 10—11 have placed a small

dab of adhesive upon the paper *p*, this dab being subsequently advanced with the advance of the paper to a position about over the block 54, shown in Fig. 3. In introducing a post card, the forks 42 of slide 41 straddle this dab of adhesive on the paper *p* and locate the post card symmetrically with the wrapping paper. Immediately thereafter the block 54 moves up to force the paper and the card together against the bottom-plate of the band-box, and the fork withdraws to the position shown in Fig. 3 where it is ready to introduce the next card. After this operation, it will be obvious that the card and the paper are stuck together by a very small patch of adhesive not large enough to mar the appearance of the card but still large enough to hold the two together. After this operation, the suction-box 31 is operated to present the leading end 70 of a band, as shown in Fig. 2, and the nipper 32 advances and in one grab grips the leading end of band and the leading end of the wrapping paper and then moves off to the wrapping elements of the machines, the 75 shears 7 operating at the proper time to sever the proper length of wrapper. It will readily be understood that the result of these operations is to present for wrapping upon the article a band and a piece of wrapping 80 paper with a card sandwiched therebetween.

In Fig. 5, I have shown a modification of my device which concerns the application of adhesive to the card, either in addition to the application of adhesive to the wrapping paper or as a substitute therefor. In this modification, I have provided a path-cam 60 upon the transverse-shaft 3 of the machine which operates the plunger 61 located in a glue-box 62 immediately under the pile 90 of cards 45. In this construction, the plunger 61 moves up to apply a dab of adhesive to the underside of the post card just before the forked slide 41 removes this card from the pile.

100 It is to be understood that in both modifications, the forked structure of the slide 41 is such as to hold the card so that the adhesive either upon the card or upon the wrapping paper, as the case may be, will 105 not be touched by the other as the card is introduced, until the contact-block 54 makes a connection between the two.

Having now particularly pointed out and described my invention, but well knowing 110 that many changes and modifications may be made from the specific forms in which I have chosen here to illustrate it without departing from the broad scope of the invention, which is more truly bounded and defined by the claims hereto appended, I claim:—

115 1. In a wrapping machine, the combination of a wrapper feed, a card feed operative to associate a card with a wrapper, and 120

125 65 adhesive devices 10—11 have placed a small 130

a device operative thereafter to transfer said card and wrapper simultaneously to the wrapping elements of the machine.

5. In a wrapping machine, the combination with a band positioning mechanism, a wrapper feed, and a card feed, all arranged to associate together a band, wrapper and card, of a device operative to transfer simultaneously the band, wrapper and card, so 10 associated, to the wrapping elements of the machine.

6. In a wrapping machine, a card feed, a wrapper feed, means to associate said card with said wrapper, including means operative to cause said card and wrapper to adhere to each other, and means to thereafter transfer said card and said wrapper to the wrapping elements of the machine.

7. In a wrapping machine, the combination of wrapping mechanism, means operative to transfer wrapping material to said wrapping mechanism, a wrapper feeding mechanism, a band feeding mechanism and a card feeding mechanism, said feeding mechanisms being arranged to feed respectively a wrapper, a band and a card one at a time to said transferring means, and said feeding mechanisms being operative to sandwich the card between the wrapper and the band.

8. In a wrapping machine, a wrapper feed, a band feed and a card feed, said feeds being arranged to sandwich the card between the wrapper and the band, means operative to cause the card to adhere to one 35 of the other members of said assemblage, and means to thereafter transfer the assembled bunch to the wrapping elements of the machine.

9. In a wrapping machine, the combination of wrapping mechanism, wrapper feeding mechanism adapted to advance wrappers one at a time, a card feeding mechanism constructed to advance cards one at a time and operative to position each card in substantially a predetermined relationship to a 45 wrapper, and means for bringing the wrapper, card and the article to be wrapped together.

10. In a wrapping machine, the combination of band feeding mechanism, wrapper feeding mechanism and card feeding mecha-

nism, said mechanisms being arranged to introduce a card between each wrapper and band, and means for applying adhesive to one of the members of said assemblage to 55 hold the card in its proper position between the wrapper and the band.

11. In a wrapping machine, the combination of wrapping mechanism, means to make a multiple wrapper including a band, a 60 wrapper sheet and a card held by adhesive matter between said band and said sheet, and means for transferring said multiple wrapper to said wrapping mechanism.

12. In a wrapping machine, a support having a guide-way, a wrapper box located above the guide-way, means to feed wrapping paper through said guide-way, means to thereafter introduce a card transversely of said guide-way to a position substantially 70 midway of and above said wrapping paper, and means to apply adhesive to one of said parts whereby when said card is introduced the adhesive will be between the card and the wrapping paper.

13. In a wrapping machine, means for feeding a wrapper, means for feeding a card, means for applying adhesive to one of the parts so fed, means to locate the card in proximity to the wrapper without disturbing 80 the adhesive, and means to thereafter press said card and said wrapper together upon the adhesive.

14. In a wrapping machine, the combination of wrapper feeding mechanism arranged to advance wrappers one at a time, a card feeding mechanism arranged to advance cards one at a time, adhesive applying mechanism operative to apply adhesive to one of the parts so advanced, said card 90 feeding mechanism including a fork constructed and arranged to transfer a card to a position above and adjacent to a wrapper without disturbing the adhesive, and a plunger operable between the tines of said fork 95 to press together said card and said wrapper upon said adhesive.
